Richardson H. Taylor

By A. J. O'Brien
Attorney

UNITED STATES PATENT OFFICE.

RICHARDSON H. TAYLOR, OF MEEKER, COLORADO.

CROWN ADAPTER.

Application filed October 19, 1922. Serial No. 595,544.

To all whom it may concern:

Be it known that I, RICHARDSON H. TAYLOR, a citizen of the United States, residing at Meeker, in the county of Rio Blanco and 5 State of Colorado, have invented certain new and useful Improvements in Crown Adapters; and I do declare the following to be a full, clear, and exact description of the invention, such as will enable others 10 skilled in the art to which it appertains to make and use the same, reference being had to the accompanying drawings, and to the characters of reference marked thereon, which form a part of this specification.

15 This invention relates to dental instruments and more particularly to an instrument to be used by dentists in fitting the edge of the crown at the gingiva in a sure and accurate manner.

20 In dental work it often becomes necessary to apply to a tooth a gold cap, generally referred to as a crown. Crowns for this purpose are supplied ready made by dental supply houses, and dentists usually carry a 25 number of assorted sizes in stock. When a tooth is to be "crowned," it is ground down to the required size and its circumference is then measured by an instrument called a dentimeter, one example of which is described and claimed by me in my co-pending application Serial Number 583,187, filed August 21, 1922. Broadly, a dentimeter is 30 an instrument by means of which a loop of soft metal wire, preferably iron, is placed 35 about the tooth and twisted into a close fit. The loop is then removed from the tooth and becomes an almost exact measurement of the tooth's circumference. A crown is then selected which is slightly smaller in 40 size than the tooth actually requires, and this is stretched to the proper size by means of my improved crown adapter, which I will now describe, reference being had for this purpose to the accompanying drawing, in 45 which—

Fig. 1 shows a plan view of my crown adapter, with the stretching points in spaced position;

Fig. 2 is a view similar to that in Fig. 1, 50 but shows the stretching points in closed position;

Fig. 3 is a view looking in the direction of arrow 3 in Fig. 2;

Fig. 4 is a view looking in the direction 55 of the arrow 4 in Fig. 1;

Fig. 5 is a fragmentary view showing a

section of a crown in place on the stretching points, which have purposely been spaced farther apart than would ordinarily occur in actual operation;

60

Fig. 6 is a section on line 6—6, Fig. 2;

Fig. 7 is a view looking in the direction of arrow 7, Fig. 5; and

Fig. 8 is a view showing the manner in which the dentimeter is used in adjusting 65 the crown adapter.

The same reference characters will be used to indicate the same parts throughout the several views.

Numeral 1 represents my crown adapter 70 as a whole, while 2 and 3 represent the two relatively movable members, which are substantially circular and are pivotally connected at their centers by means of a bolt 4, or other suitable means. A handle 5 is 75 formed integral with or otherwise rigidly secured to the movable member 3, while a similar handle member 6 is secured to member 4. A screw 7 passes through one of the handles (6) and has its end so positioned 80 that it will engage the shoulder 8 on the handle 5 and serve as a stop by means of which the movement of the handles towards each other can be limited. Secured to the periphery of the member 2 are a number 85 of curved, outwardly-projecting stretching points A, A¹, A², A³, A⁴ and A⁵, and secured to corresponding points on the periphery of member 3 are co-operating points B, B¹, B², B³, B⁴ and B⁵. The points 90 A and B are so arranged with respect to each other that when the handles 5 and 6 are spread apart as shown in Fig. 2, the points approach each other to the position shown in Fig. 3, and when the handles are 95 brought together to the position shown in Fig. 1, the points move apart to the position shown in Fig. 4. It is evident that if a ductile band such as a crown or a matrix 9 (Figs. 5 and 7) be placed about any pair 100 of points when they are in the position shown in Figs. 2 and 3 and the handles moved to the position shown in Fig. 1, the movement of the points to the position shown in Figs. 1, 5 and 7 will stretch the 105 band, the amount of stretching being determined by the position of the screw 7. It is evident that, since the spreading points move about a central point, the outer sides thereof can only be parallel at a single 110 position. I therefore construct my spreading points so that the circumference is

slightly less at the tips than at the base when the instrument is in the position shown in Fig. 2, and approximately equal when the points have moved apart the distance usually found necessary to produce the required stretching. The advantage of having the spreading points move about a central point and from an outwardly tapering position to a parallel position instead of in a constantly parallel position, as would be the case if they moved in a straight line, is that where a cylindrical band or ring is placed on the pins to be stretched, the metal will probably yield a little more readily if it starts at one edge and then finally becomes equal for the whole transverse area. The slight taper also enables me to more readily fit the band onto the stretching points.

20 The circular movement is also of great advantage where it is necessary to stretch the upper part of the crown close to the top thereof, so as to make it larger at the top than at the bottom. The crown is merely put onto a smaller pair of points, which are then moved into the position shown in Fig. 5.

The operation of my device is as follows. After the tooth has been ground down to the desired size, its circumference is determined by employing an ordinary dentimeter 30 (Fig. 8). The loop 11 is then fitted about the nearest pair of points in the manner shown in Fig. 8, the handles are pressed gently together until the loop 11 becomes taut, and the screw 7 is adjusted to this position. The adapter is then moved to the position shown in Fig. 2, and a crown is selected and applied to the stretching points, after 40 which the handles are pressed together, which spreads the points and stretches the crown to the required size.

In order to accommodate crowns of all different sizes, from a small lower incisor to a large molar, without materially changing the shape of the circumference, I provide a number of pairs of stretching points (six pair shown) of different sizes.

It is apparent from the above that I have produced an instrument that will permit a dentist to quickly and conveniently stretch a crown to a predetermined size, and where necessary, to enlarge the upper end thereof to a greater diameter than the lower.

Having now described my invention, 55 what I claim is:

1. A crown adapter comprising two members relatively rotatable about a common pivot, a plurality of pairs of stretching points secured to the peripheries of said members, and means for rotating the members.

2. A crown adapter having two members pivotally connected, a handle secured to each member, a plurality of pairs of stretching points secured to the peripheral edges, one member of each pair being secured to each pivoted member and adapted to be moved towards or away from each other as the members are relatively rotated about the pivot, and a stop for limiting the spreading movement of said points.

3. A crown adapter having two members pivotally connected, a handle secured to each member, a plurality of pairs of stretching points secured to the peripheral edges, one member of each pair being secured to each pivoted member and adapted to be moved towards or away from each other as the members are relatively rotated about the pivot, and an adjustable stop for limiting the spreading movement of said points.

4. A crown adapter consisting of two flat, substantially circular members pivotally connected at their centers, a number of stretching points secured at spaced intervals about the periphery of each member, each point on one member co-operating with a complementary point on the other member, a handle secured to each member whereby they may be relatively rotated, and a stop means secured to said handles for limiting their movement to a predetermined amount.

In testimony whereof I affix my signature.

RICHARDSON H. TAYLOR.
